UNITED STATES PATENT OFFICE.

ALEXANDER P. WHITE, OF CALDWELL, NEW JERSEY, ASSIGNOR TO THE GENERAL FIREPROOFING COMPANY, A CORPORATION OF OHIO.

METALLIC STRUCTURE.

1,199,137.

Specification of Letters Patent. Patented Sept. 26, 1916.

Application filed November 13, 1909. Serial No. 527,756.

To all whom it may concern:

Be it known that I, ALEXANDER P. WHITE, a citizen of the United States, residing in Caldwell, county of Essex, State of New Jersey, have invented certain new and useful Improvements in Metallic Structures, of which the following is a specification.

My invention relates to metallic boxes, drawers, cases, cabinets, and the like, and particularly to metallic structures of this variety which are assembled and fastened together without the use of rivets, and the object of my invention is to improve and cheapen the construction. The method of assembling and locking the parts together is so simple that the structures may be shipped in knocked-down form and put together by the purchaser or user without requiring any particular skill or the use of special tools. I accomplish this object by having two of the sides integral with or hinged to a third side, and providing the other side or sides with flanges which interfit with flanges on the third side and with a key frame, said frame also engaging flanges on the free ends of the first two sides. By fastening the key frame in place all of the elements are connected and fastened together.

Referring to the accompanying drawings, Figure 1 is a perspective view of an assembled structure embodying my invention; Fig. 2 is a vertical section on the line 2—2 of Fig. 1; Fig. 3 is a vertical section on the line 3—3 of Fig. 1; Figs. 4 and 5 are perspective views of the elements which are to be assembled. Fig. 6 is a detail view of the corner of a side; Fig. 7 shows a corner of the key frame with the sides of the structure in their final position in dotted lines; Fig. 8 shows the manner in which two of the sides may be hinged to a third; Figs. 9 and 10 show a modification of the flanged connection between the sides.

For convenience, the structure will be considered in the position shown in Fig. 1, so that the elements may be referred to as top, bottom, back and sides.

In the preferred form of my invention the back 1, and the sides constituting the top 2 and the bottom 3 are bent up from one metal sheet, and flanges 4, 4 are formed on the vertical edges of the back. The front or free edges of the top and bottom are also provided with flanges 5, 5, and the corners are

cut away as at 6, 6 to receive the key frame. The flanges 5, 5 may be provided with tabs 7, 7 to be folded over the key frame as hereinafter explained.

The side pieces 8 are exactly alike, except they are made right and left, and each is provided with a rear flange 9 and a front flange 10. The corners of the front flange must be cut away, as at 11, to receive the key frame. The sides may also be provided with flanges 12, 12, for the purpose of giving finish and strength. In some cases only one side is used.

The key frame 13 is merely a metal square, the width of each side being just sufficient to allow the frame to slide under the flanges.

To assemble the structure, the free ends of the top and bottom, that is to say, the flanges 5, 5, are forced toward each other, as shown in Fig. 4. The key frame 13 is then slipped over the ends into the position shown in Fig. 4, and pushed back until it abuts against the rear shoulder of the cut away corners 6, 6. The corners 6, 6 must be cut away far enough back to allow the tabs 7, 7 to pass up in front of the key frame when the top and bottom are sprung or forced back to their normal position. The side pieces 8 are then adjusted in position with the rear flange 9 engaging with the flange 4 on the back of the structure, and the front flange 10 overlapping the key frame between the top and bottom flanges 5, 5. With the parts in this position, the key frame is back of the flanges 5, 5 and 10, 10, and in order to connect the parts the key frame is forced forward so that it passes under all four of these flanges.

In order to prevent the key frame from sliding back into its rear position where the parts might become disconnected, the tabs 7, 7 are folded down so as to act as stops. The position of the key frame after it has been pushed forward is clearly indicated in Fig. 7. Instead of having the top and bottom integrally connected to the back, they may be connected by the well known form of hinge indicated in Fig. 8.

In Figs. 9 and 10 I show a modification of the method of connecting the side to the back, in which the slots 14, 14 take the place of the rear flange 4; and the tabs 15, which are adapted to register with the slots 14, take the place of the flange 10.

For the purpose of rigidity and strength I

prefer to make the key frame in the form of a square, as shown in the drawings, but obviously the central portion of the vertical sides of the key frame, as it is shown in Fig. 4, may be omitted between the lines 16—16, because when the parts are assembled the flange 10 prevents displacement of the upper and lower sides of the key frame, and as the upper and lower portions of the key frame are locked under the flanges 5, 5, the top and bottom of the structure will be held in position even though the key frame itself is not solid.

Other modifications of the mechanical details and arrangements of the parts will occur to those skilled in this art, and other means for locking the key frame in position, and I do not limit myself to the details herein shown and described, for I consider that my invention consists broadly in a key frame adapted to engage flanges on three or four of the sides of a structure of this class, two of those sides being permanently connected to the fourth or fifth, and the other one or two being connected to the fourth or fifth by interfitting flanges.

Having described my invention, what I claim is:

1. In a metallic structure, the combination of a back provided with flanges, a top and a bottom integrally connected to said back and provided with flanges at their front edges adapted to engage with a key frame, two sides provided with rear flanges adapted to engage with the flanges on said back, and front flanges adapted to engage with a key frame, and a key frame adapted to engage with the front flanges on the top, bottom and sides and adapted to be operated from the outside of the structure.

2. In a metallic structure, the combination of a back provided with flanges, a top and a bottom integrally connected to said back and provided with flanges at their front edges adapted to engage with a key frame, two sides provided with rear flanges adapted to engage with the flanges on said back, and front flanges adapted to engage with a key frame, a key frame adapted to engage with the front flanges on the top, bottom and sides, and means for locking said key frame under said flanges, said locking means and frame adapted to be operated from the outside of the structure.

3. A metallic structure comprising a back having two sides secured thereto and movable relative to each other, a single rigid key frame having an opening larger than the in-

ner surface of the back and adapted to seat over the sides when same are bent toward each other, separate side pieces detachably secured to the back and means on each of said side pieces adapted to interlock with the frame.

4. A metallic structure comprising a back having two sides secured thereto and movable relative to each other, a single rigid key frame adapted to slip over the free ends of said sides when they are bent toward each other, separate side pieces detachably secured to the back, and means provided on the free ends of said side pieces adapted to interlock with the frame when the same is moved in a direction away from the back and to conceal the same.

5. In a metallic structure, the combination with a back and two sides connected thereto, of two side pieces detachably connected to said back and a key frame engaging the free ends of said sides and side pieces to lock the same in position.

6. In a metallic structure, the combination with a back and two sides connected thereto, of two side pieces detachably connected to said back, each of the side pieces attached to said back and having a flange at the free end thereof and a key frame engaging said flanges to hold the same in position relative to each other.

7. In a metallic structure, the combination with a back and two sides connected thereto, of two side pieces detachably connected to said back, each of the sides attached to said back having a flange, a key frame engaging said flanges and means for holding said flanged sides in position on the key frame.

8. In a metallic structure, the combination of a side-piece having exterior flanges on opposite edges thereof, and two side-pieces connected to the other opposite edges and provided with exterior flanges at their free ends, a key-frame adapted to engage with the exterior flanges on the free ends of said two sides, two other side-pieces provided with interior flanges adapted to engage with the exterior flanges on the first-mentioned side-piece, and also provided with interior flanges adapted to engage with said key-frame.

In witness whereof I have hereunto set my hand, in the presence of two witnesses.

ALEXANDER P. WHITE.
